ELMER BERRY BRUMFIELD AND ARTHUR OLIN HICKOK, OF TULSA, OKLAHOMA.

WELL-TUBING CAGE.

Application filed December 2, 1925. Serial No. 72,779.

Our invention relates generally to well tubing, more particularly to an improved so-called "cage" for use in a producing oil well in conjunction with a well packer, and it consists in the combinations, constructions and arrangements herein described and claimed.

An object of our invention is to provide a cage which is adapted to prevent flow from the well casing into the well tubing below a packer when the packer and the cage are placed in the well casing but which can be operated when in position in the well casing to permit or prevent flow from the well casing into the well tubing, as desired.

A further object of the invention is the provision of a cage of the character described which is reliable in use, easy to operate and not likely to get out of order easily.

Other objects and advantages of the invention will be apparent from the following description, considered in conjunction with the accompanying drawings, in which

Figure 1 is a longitudinal vertical section through a portion of a well casing, showing in elevation a well tubing, in the casing, a cage embodying the invention disposed between sections of the well tubing, the cage being closed, and a packer in the well casing above the cage.

Figure 2 is a view similar to Figure 1, showing the cage open.

Figure 3 is a relatively enlarged fragmentary sectional view similar to Figure 1, showing the details of construction of co-operative elements of the cage and the means for operating it.

Figure 4 is a still further enlarged section taken substantially along the line 4-4 of Figure 3, and

Figure 5 is a fragmentary longitudinal vertical section through the cage.

When a packer is placed in the casing of a producing oil well around the well tubing, a "cage" is positioned between sections of the well tubing for the purpose of permitting flow below the packer from the casing into the well tubing when the work of securing the packer in the well casing and securing additional sections of the well tubing in place above the packer has been accomplished. Prior to our invention, all such cages of which we are aware were open when lowered in the well casing and therefore considerable leakage from the well casing below

the packer would take place through the well tubing while additional sections were being added to the well tubing above the packer or while the well tubing was open above the packer for any cause.

Our invention obviates the objectionable feature just mentioned of prior cages by providing a cage which is closed to flow from the well casing thereinto when the cage is lowered to position in the well casing and which can be opened conveniently and easily when desired after it has been lowered to position in the well casing to permit flow from the well casing into the cage and thence upwardly in the well tubing.

In Figures 1 to 3 inclusive, the numeral 1 designates a well casing. A well tubing in the casing 1 includes a section 2 which is surrounded by a casing packer 3, a section 4 having its upper end portion connected with the section 2 by a union 5, a cage embodying the invention and generally designated 6, and a section 7 which is connected with the section 4 by the cage 6.

The cage 6 comprises a tubular body 8 enlarged externally adjacent to its upper end as at 8^a, thus defining an annular shoulder 9 at the lower end of the enlargement. The shoulder 9 preferably is undercut and beveled as indicated at 10. The enlarged upper end portion of the tubular body is enlarged internally at 11 and provided with screw threads for engaging with the externally

screw threaded lower end portion of the section 4 of the well tubing. A collar 12 is secured by welding or in any other suitable known manner on the tubular body 8 in spaced relation to the shoulder 9 and in

position to cooperate with the beveled portion of the shoulder 9 to retain a rotary sleeve valve 13 against axial movement on the tubular body, the rotary sleeve valve and the portion of the tubular body encircled by

the sleeve valve being formed with a like number of circumferentially spaced elongated ports 15 and 16, respectively, whereby the sleeve valve 13 can be turned on the tubular body to position the respective ports 15 in

register with the corresponding ports 16 or out of register with such ports. The sleeve valve 13 carries spaced spring fingers having inturned rounded lower end portions f' adapted to engage with depressions d in the upper end portion of the collar 13 to prevent

accidental turning movement of the sleeve valve on the body 8 from either open or

closed positions without preventing operation of the sleeve valve in a manner to be presently described. The sleeve valve 13 preferably has the upper end portion thereof beveled to complement the beveled portion 10 of the shoulder 9. The collar 12 has an annular prolongation or reduced portion 12^a at its upper end provided with a beveled outer wall and the lower end of the sleeve valve 13 is beveled to complement the beveled wall of the reduced end portion 12^a of the collar 12. The collar 12 may depend below the lower end of the tubular body 8 and may have the lower end portion thereof internally screw threaded for engaging with the externally screw threaded upper end portion of the section 7 of the well tubing.

The upper end portion of the sleeve valve carries a circumferential series of spaced radial projections consisting of rollers 17 mounted on radial pins 18 having the inner end portions thereof in threaded engagement with sockets in the sleeve valve. The purpose of the radial projections on the sleeve valve will be presently described.

Spaced slide rings 19 and 20, respectively, on the section 4 of the well tubing are connected by four equi-distantly spaced spring friction latch members 21 which are bowed outwardly intermediate their ends a distance sufficient to bear with considerable pressure against the inner wall of the casing 1, the outer wall of each of the spring latch members 21 preferably being roughened as indicated at 22 where it contacts with the inner face of the casing 1. The upper end of each of the spring members 21 fits in a socket 23 in the lower end of the slide ring 20 while the lower end portion of each spring member 21 is loosely received in a socket 24 in the upper end of the slide ring 19, being retained in the socket 24 by a pivot pin 25 which extends through aligned transverse openings 26 and 27 in the member 21 and the ring 19, respectively. An adjusting screw 28 is threaded through a radial opening in the ring 19 into the lower end of each socket 24 and bears against the lower end of the spring member within the socket below the associated pivot pin 25, whereby the pressure which the member 21 will exert on the inner wall of the casing 1 can be adjusted within limits by manipulation of the screw 28.

The ring 19 is enlarged downwardly to provide diametrically opposite lugs 29 having sockets as at 30, in their lower ends in which substantially radial pivot elements 30^a are arranged to support the upper end portions of longitudinally curved elongated cam members 31 which extend downwardly along opposite sides of the section 4.

The ring 19 is held against rotation on the section 4 of the well tubing by longitudinal guide ribs 32 which are provided

on the section 4 and engage with longitudinal grooves 33 in the inner wall of the ring 19. The cam members 31 therefore will be held against swinging about the axis of the section 4.

From the foregoing description of the various parts of the device, the operation thereof may be readily understood. The rotary sleeve valve 13 is turned to closed position before the cage is lowered to a desirable position in the well casing. After the cage is in position in the well casing, the tubing is raised a slight distance. The engagement of the spring friction latching members 21 with the inner wall of the casing will hold the rings 19 and 20 and the cam members 31 substantially stationary in the casing. The upward movement of the well tubing will result in certain of the radially projecting rollers 17 on the rotary sleeve valve contacting with the cam members 31, whereby further upward movement of the well tubing will cause the rotary sleeve valve 13 to be turned on the tubular body 8 of the cage to open position. The enlarged upper end portion 8^a of the body of the cage serves as a stop for limiting the relative axial movements of the well tubing and the ring 19 when the well tubing is being moved upward and the union 5 serves as a stop for limiting the relative axial movements of the ring 20 and the well tubing when the well tubing is moving downward. The rings 19 and 20 of course are connected by the spring members 21 to move substantially in unison.

It is to be observed at this point that the lateral distance from the plane of the upper end portion to the plane of the lower end portion of each elongated cam member 31 is greater than the distance between adjacent radially projecting rollers 17. Consequently, the rotary sleeve valve can again be closed when desired after it has been opened in the manner described by lowering the tubing in the well bore relatively to the ring 19 and cam members 31, the lower end portions of the cam members contacting with other of the rollers 17 and the sleeve 13 being turned to closed position. Slight swinging movement of the cam members 31 in one direction about the axes of the pivot elements 30^a may take place against the action of spring arms 30^b to permit disengagement of the last named radially projecting rollers 17 after the sleeve 13 has been closed.

Obviously, our invention is susceptible of embodiment in forms other than that which is illustrated in the accompanying drawings and we therefore consider as our own all such modifications and adaptations thereof as fairly fall within the scope of the appended claims.

We claim:

1. A device of the character described

comprising a tubular body having a lateral port and adapted to be lowered in a well casing, a rotary valve controlling said port, and means actuated when the tubular body is moved in one direction in the well casing to turn said valve on said tubular body.

2. A device of the character described comprising a tubular body having a lateral port and adapted to be attached at its ends to lengths of well tubing and lowered in a well casing, a rotary valve controlling said port, and means actuated when the tubular body is raised in the well casing to turn said valve on said tubular body, said valve opening means including spring members in frictional contact with the inner wall of the well casing and movably mounted on the length of well tubing above said tubular body, a projection on said valve, and a cam member connected with the spring members for engaging with said projection to turn said valve when said tubular body is moved axially in the well casing independently of the spring members.

3. A device of the character described comprising a tubular body having a lateral port and being attachable at its ends to lengths of well tubing and adapted to be lowered in a well casing, a rotary sleeve valve on said tubular body, said sleeve valve having a lateral port movable to and from position to register with the port of the tubular body as the sleeve valve is rotated on the tubular body, a lateral projection on the upper end of the sleeve valve, and means movably mounted on the well tubing above said tubular body for engaging with the lateral projection when the tubular body is raised in the well casing to turn the sleeve valve on the body.

4. A device of the character described comprising a tubular body having a lateral port and being attachable at its ends to lengths of well tubing and adapted to be lowered in a well casing, a rotary sleeve valve on said tubular body, said sleeve valve having a lateral port movable to and from position to register with the port of the tubular body as the sleeve valve is rotated on the tubular body, a lateral projection on the upper end of the sleeve valve, a ring slidably mounted on the well tubing above said sleeve valve and held against turning on the well tubing, means carried by said ring in frictional engagement with the inner wall of the well casing, tending to hold said ring against movement in the well casing, and a longitudinally curved cam member depending from said ring for engaging with said lateral projection on relative movement of the tubular body and the ring to effect turning of the sleeve valve.

5. A device of the character described comprising a tubular body having a lateral port and being attachable at its ends to

lengths of well tubing and adapted to be lowered in a well casing, a rotary sleeve valve on said tubular body, said sleeve valve having a lateral port movable to and from position to register with the port of the tubular body as the sleeve valve is rotated on the tubular body, a lateral projection on the upper end of the sleeve valve, a ring slidably mounted on the well tubing above said sleeve valve and held against turning on the well tubing, means carried by said ring in frictional engagement with the inner wall of the well casing, tending to hold said ring against movement in the well casing, and a longitudinally curved cam member depending from said ring for engaging with said lateral projection on relative movement of the tubular body and the ring to effect turning of the sleeve valve, said lateral projection comprising a radial shaft and a roller mounted on the shaft.

6. A device of the character described comprising a tubular body having a lateral port and being attachable at its ends to lengths of well tubing and adapted to be lowered in a well casing, a rotary sleeve valve on said tubular body, said sleeve valve having a lateral port movable to and from position to register with the port of the tubular body as the sleeve valve is rotated on the tubular body, a plurality of spaced radial projections on the upper end portion of said sleeve valve, a pair of spaced rings slidably mounted on the well tubing above said tubular body, said rings having alined sockets in the adjacent ends thereof, an outwardly bowed spring member for each pair of alined sockets, the bowed portion of said spring members frictionally contacting with the inner wall of the well casing, the upper end of each spring member being secured in a socket of the upper ring and the lower end portion of the spring member extending loosely in the corresponding socket of the lower ring, a transverse pivot element supporting the lower end portion of each spring member in its socket in the lower ring, an adjusting screw threaded in a radial opening in the lower ring against the outer face of each spring member below said transverse pivot element for adjusting the pressure of the spring member on the inner wall of the well casing, and a plurality of spaced longitudinally curved cam members depending from the lower ring for engaging with the projections on the sleeve valve to rotate the latter.

7. A device of the character described comprising a tubular body having a lateral port and being attachable at its ends to lengths of well tubing and adapted to be lowered in a well casing, a rotary sleeve valve on said tubular body, said sleeve valve having a lateral port movable to and from position to register with the port of the tubular body as the sleeve valve is rotated on

the tubular body, a lateral projection on the upper end of the sleeve valve, means movably mounted on the well tubing above said tubular body for engaging with the lateral projection when the tubular body is raised in the well casing to turn the sleeve valve on the body and a stop on the well tubing above said sleeve valve operating means.

8. A device of the character described comprising a tubular body having a lateral port and being attachable at its ends to lengths of well tubing and adapted to be lowered in a well casing, a rotary sleeve valve on said tubular body, said sleeve valve having a lateral port movable to and from position to register with the port of the tubular body as the sleeve valve is rotated on the tubular body, a plurality of spaced radial projections on the upper end portion of said sleeve valve, a pair of spaced rings slidably mounted on the well tubing above said tubular body, outwardly bowed spring members connecting said slide rings, the bowed portion of said spring members frictionally contacting with the inner wall of the well casing, a plurality of spaced longitudinally curved cam members depending from the lower ring for engaging with the projections on the sleeve valve to rotate the latter, the lateral distance between the planes of the upper and lower ends of each cam member being greater than the distance between adjacent radial projections on the sleeve valve, each of said cam members being capable of limited swinging movement about its pivotal support, and a spring member resisting swinging movement of each cam member in one direction about its pivotal support.

9. A device of the character described comprising a tubular body having a lateral port and adapted to be attached at its ends to lengths of well tubing and lowered in a well casing, a rotary valve controlling said port, said valve being adapted to remain closed when the tubular body is lowered in the well casing, and means actuated when the tubular body is raised in the well casing to open said valve and when the tubular body subsequently is lowered and raised again in the well casing to close said valve.

10. A device of the character described comprising a tubular body having a lateral port and being attachable at its ends to lengths of well tubing and adapted to be lowered in a well casing, a rotary sleeve

valve on said tubular body, said sleeve valve having a lateral port movable to and from position to register with the port of the tubular body as the sleeve valve is rotated on the tubular body, a plurality of spaced radial projections on the upper end portion of said sleeve valve, a pair of spaced rings slidably mounted on the well tubing above said tubular body, outwardly bowed spring members connecting said slide rings, the bowed portion of said spring members frictionally contacting with the inner wall of the well casing, a plurality of spaced longitudinally curved cam members depending from the lower ring for engaging with the projections on the sleeve valve to rotate the latter, the lateral distance between the planes of the upper and lower ends of each cam member being greater than the distance between adjacent radial projections on the sleeve valve, each of said cam members being capable of limited swinging movement about its pivotal support, and a spring member resisting swinging movement of each cam member in one direction about its pivotal support.

11. A device of the character described comprising a tubular body having a lateral port and being attachable at its ends to lengths of well tubing and adapted to be lowered in a well casing, a rotary sleeve valve on said tubular body, said sleeve valve having a lateral port movable to and from position to register with the port of the tubular body as the sleeve valve is rotated on the tubular body, means for operating said sleeve valve, and spring means acting to prevent accidental turning movement of said sleeve valve on the tubular body.

12. A device of the character described comprising a tubular body having a lateral port and being attachable at its ends to lengths of well tubing and adapted to be lowered in a well casing, a rotary sleeve valve on said tubular body, said sleeve valve having a lateral port movable to and from position to register with the port of the tubular body as the sleeve valve is rotated on the tubular body, means for operating said sleeve valve, and spring means acting to prevent accidental turning movement of said sleeve valve on the tubular body, said spring means comprising spring fingers on the lower end portion of said valve, and a member on said tubular body below said valve having circumferentially spaced depressions for engaging with the lower end portions of said spring fingers, said lower end portions of said spring fingers being turned inwardly and rounded at their extremities.
